UNITED STATES PATENT OFFICE.

ERNEST UNGER, OF NEW YORK, N. Y.

PROJECTING-LANTERN.

1,130,451.

Specification of Letters Patent. Patented Mar. 2, 1915.

Application filed March 6, 1913. Serial No. 752,292.

To all whom it may concern:

Be it known that I, ERNEST UNGER, a citizen of the United States, residing in the city, county, and State of New York, have invented certain new and useful Improvements in Projecting-Lanterns, of which the following is a specification.

My invention relates to a projecting lantern and particularly relates to those lanterns in which the source of light is an electric arc.

The primary object of my invention is to provide an inexpensive lantern having all the necessary adjustments now characterizing expensive devices of this character, but which is constructed of relatively few parts and these parts of the simplest construction and assembled to perform the objects of a device of this character with a sufficient refinement of adjustment in the several parts for the general uses to which these lanterns are put.

The invention further consists of other new and novel parts and combination of parts all as more fully hereinafter set forth.

Reference is to be had to the accompanying drawings in which similar reference characters indicate corresponding parts and in which—

80. Figure 1 is a perspective view showing a preferred embodiment of my invention with the parts in collapsed position. Fig. 2 is a vertical longitudinal sectional view taken substantially through the center of the device shown in Fig. 1, certain parts being in side elevation. Fig. 3 is a vertical transverse sectional view taken on the line 3—3 of Fig. 2 looking forward or in the direction indicated by the arrows, and Fig. 4 is 85 a similar view taken on the line 4—4 of Fig. 2 looking rearwardly or in the direction indicated by the arrows on this line.

Described more in detail my device comprises a base A preferably of relatively wide extent and of heavy material so as to form a broad substantial unitary base for the device. Projecting centrally from above the top of this base is a pair of transmitting spaced apart lugs B preferably formed integral with the base A and having some resiliency, mounted between which lugs is the depending co-acting longitudinally extending tongue or disk C forming a relatively wide bearing with the lugs B and 90 frictionally held in engagement therewith

by means of a binding screw D or other suitable fastening device. The member C like the support A is of heavy material and is rigidly attached to and preferably forms an integral part of a wide bottom and narrow 60 top band forming an inclosing frame E for the cylindrical condenser cell. Formed integral with the frame E and extending downwardly and outwardly from the opposite lower sides thereof are the depending 65 long arms F having tubular outer portions G for the purpose hereinafter more fully disclosed. The front of the frame E is outlined by an outstanding rim H adapted to constitute a support for the slide carrying box I which box is adapted to contain a conventional form of slide frame J as is common with devices of this character.

In order to conveniently mount this slide carrying box I upon the frame E so that the same may be conveniently dismounted or rotated in its own plane, there are extending from opposite lower sides of the rear face 10 of the box I a pair of outstanding L shaped clips 11 a finger 12 of which is adapted to lap and bind against the rear face of the flange H. To lock the frame in its adjusted position there is extending from the box I and preferably from the top 13 thereof an overhanging bracket 14, in a vertical bearing in the end 15 of which is mounted a thumb screw 16 which thumb screw is adapted to engage the top of the frame E in rear of the flange H. By this construction it is seen that loosening the 85 screw 16 of the box I can be rotated in its own plane about the axis of the cylinder as a center of rotation and when in the desired position the screw 16 may be brought into binding contact with the outside of frame E drawing the clips 11 into firm engagement with the rim H. Should it be desired to entirely dismount the box I, the screws 16 may be rotated until the free end thereof can be disengaged from the flange 100 H and by dropping the box I the fingers 12 can be disengaged from the flange H. As shown in this embodiment of the invention the front of the box I carries the frustoconical hood or funnel 17, which when the 105 device is collapsed into the position shown in Fig. 1 telescopes within the correspondingly shaped hood 18 forming a rearward extension of the objective casing 19. This objective casing 19 is of conventional form 110

having a plurality of field lenses 20 controlled by the focusing screw 21 as is common with devices of this character.

Rigidly mounted in the tubular portions 5 G are a pair of longitudinally extending open ended tubes 22 slidably mounted in which are the longitudinally extending rods 23 the forward ends of which are rigidly connected to the depending divergent legs 10 24 forming an integral part of the casing 19. By this construction it is seen that the objective casing 19 and its containing parts are mounted in relatively long bearings formed by the tubes 22 and that they may 15 be manually adjusted relative to the condenser and other portions of the lantern. The rods may be locked in position by any binding means, a convenient device of this character being illustrated in Fig. 1 in which the end of one of the tubes 22 is split and externally screw threaded which end is engaged by a binding mill headed screw ring 25 adapted to force the end of the tube into frictional engagement with the rods 23. 20 The condenser casing comprises in addition to the frame E a rearwardly extending cylindrical sheet metal tube 26 having apertures 27 in the bottom thereof forming air inlets and an air outlet 28 is disposed at 25 the top thereof. Further the rear edge of this tube 26 has a cut away recess portion 29 adapted to accommodate an electrode, hereinafter described, when the device is in its fully collapsible position. Further the 30 top portion of this cylinder 26 is cut away as shown at 30 for a distance from the top substantially half way to the bottom on each side in order to afford a substantially semi-cylindrical opening for the insertion 35 and withdrawal of the condenser lenses 31. The forward of the pair of condenser lenses shown is backed against an inwardly extension apertured plate 32 constituting the back of the box I and the bottom of this 40 lens is held dismountably in position by means of the forward end 33 of a holding clip 34 which clip is fastened by rivet 35 to the casing 26. The rear end of this clip 34 has an upturned edge 36 which co-acts 45 with a longitudinally spaced upturned edge 37 on a plate 38 also held by the rivets 35, which edges 36 and 37 constitute a housing or pocket for the lower edge of the rear lens 31, which rear lens is mounted substantially 50 midway in the opening 30 and is held in this position convenient for dismounting by means of the spring side clips 39 fastened to the tube 26. By this construction it is 55 seen that the condenser lenses 31 are removably mounted in place without the necessity of any material adjustment of fastening means as is common with the similar devices now known. The opening 30 is conveniently closed by means of a band 40 telescopically and slidably mounted upon the 60

cylinder and in frictional engagement therewith.

Telescoping the cylinder 25 and preferably spaced a short distance therefrom on all sides to permit the sliding of the sleeve 70 40 therebetween and also to provide an air passage from the inlets 27 through the outlet 28 is a cylinder of sheet metal 41 having a plurality of air outlets 42 disposed about the top surface thereof and offset from the outlet 28 so as to prevent the emission of light from the arc hereinafter described and yet to provide a convenient passage for the heated air within the lamp house. The cylinder 41 has a rear closure or wall 72 preferably a casting, the cylinder 41 and rear wall 72 constituting a lamp house for the electric arc or other source of light. This rear wall is preferably of cast metal and has extending from opposite lower portions 85 therefrom diverging legs 43 the outer ends of which are of cylindrical form and are connected to the rear end of a long sleeve 44 slidably mounted upon the tube 22 and telescoping the same. By this construction it 90 is seen that by grasping the knob or handle 45 the housing may be adjusted to vary the position of the arc carried within the housing, relative to the stationary condensing lenses 31. 95

In devices of this character it is desirable to mount the electrodes adjustably in position so that they may be readily replaced and manipulated without expensive clamping and adjusting means and with this object in view I provide an opening 46 centrally of the rear wall 72 and position in this opening a sleeve 47 which extends into the lamp house for some material distance and has a longitudinally split inner end 48 adapted to frictionally bind the carbon or other electrode 49, which extends therethrough from the outside of the wall 72. The rear end of the tube 47 extends to the outside of the opening 46 and terminates in 105 a laterally extending reinforcing head or plate 50 closing the opening 46, which head is insulated from the rear wall 72 by means of an insulation 51 in the form of a mica or some similar plate and the metal plate 110 50 is held in position by means of the insulated screws 52. A binding post 53 is in screw threaded engagement with the plate 50 and constitutes a means for electrically attaching one of the electric leads 54 to the 115 electrode 49. The electrode 49 may be made of carbon or any other suitable conducting material and for the purpose of manipulating the same there is in frictional engagement with the outer end thereof an insulated cap or handle 74, which cap may be readily withdrawn and inserted on the 120 end of a new carbon. 125

Mounted upon the outside of the cylinder 41 and extending through an opening 55 in 130

the lower side thereof, a short distance from the wall 72, is a sleeve 56 similar in construction to the sleeve 47 and adapted to bring a second electrode 76 into arcing engagement 5 with the electrode 49 and substantially at right angles thereto. The plate 57 corresponds to the plate 50 but is curved to fit the configuration of the cylinder 41 and is fastened thereto by means of the insulated 10 bolts 58; the plate itself is insulated from the bolts and from the casing 41 by means of the insulating material 59 disposed therebetween. The outer end of the electrode 56 is capped by an insulating handle 60 corresponding to the handle 74. Mounted upon the plate 57 is the binding post 70 to which is attached the electric lead 61 of opposite polarity to the lead 54. The split sleeves 47 and 56 gently bind their respective electrodes 15 so that by looking through the ruby glass covering opening 62 in the wall 72 the operator is enabled to observe and adjust the position of the electrodes relative to each other to attain the desired arc. By loosening 20 the screw 63 carried by one of the sleeves 44 the lamp house as a whole, carrying with it the source of light, may be adjusted relative to the lens 31 and by loosening the binding nut or ring 25 the frame or carriage 19 carrying the objective lens may be adjusted 25 relative to the stationary condenser lens. It is noted from this disclosure that applicant needs but one base A and the condenser which is relatively stationary is mounted 30 pivotally upon this base thereby affording a convenient means for adjustment in a vertical plane. At the same time the rods 22 extend forwardly and rearwardly to afford a long bearing for the objective casing 19, this 35 bearing extending entirely through the tube 22 which also affords a long extensive longitudinal bearing for the sleeve 44 which in turn supports the lamp house.

It is noted that the slide carrying box I 45 is conveniently mounted in position affording ease of adjustment by merely loosening the screw 16 and with a further adjustment of the screw 16 the entire box may be conveniently withdrawn from the condenser 50 casing.

The means for mounting the carbon may be readily and cheaply constructed being merely a split end and headed metal tube and particular attention is called to the extent to which the source of light may be 55 spaced from the objective lens and the com-

pactness with which the device can be collapsed for shipment or storage.

Having thus described my invention, what I claim to be new and desire to protect by Letters Patent is:—

1. A lamp house for projecting lanterns comprising a sheet metal cylinder open at one end, a rigid plate attached to the cylinder and closing the other end of the same, 65 said plate having a pair of spaced extensions projecting below the cylinder, long parallel tubes fixed to said extensions, rods telescoping within said tubes for supporting the lamp house, means for slidably mounting 70 an electrode in position in said plate and other means adjacent said rigid plate for mounting a coacting electrode in the wall of said sheet metal cylinder, said last named means including a plate affixed to the wall to 75 transmit strains on the coacting electrode over a relatively large area of the sheet metal wall.

2. In a projecting lantern, a lamp house comprising a light sheet metal cylinder, a 80 relatively heavy strain resisting cast metal wall for one end of said cylinder, means attached to said cast metal wall for slidably mounting said house, an electrode held in adjustable position in the rear wall and a 85 second electrode extending through and held in said sheet metal cylinder and means reinforcing said sheet metal cylinder about said second electrode to distribute the strains on said second electrode. 90

3. A lamp house for projecting lanterns comprising a relatively heavy band having depending arms with tubular portions, longitudinal rods mounted in said tubular portions and extending rearwardly therefrom, a 95 sheet metal tube supported from said band and extending rearwardly therefrom, a sheet metal cylinder telescoping said sheet metal tube and movable relative thereto, a rear closing wall for said tube fixed to said cylinder, long sleeves fixed to said rear wall and slidably mounted on the rearwardly extending portion of said longitudinal rods, said tube and cylinder being independently supported and means integral with the band 100 for supporting the latter. 105

In witness whereof I have hereunto set my hand in the presence of two witnesses.

ERNEST UNGER.
